Inventor:

David E. Roe.

United States Patent Office.

DAVID E. ROE, OF ELMIRA, NEW YORK.

Letters Patent No. 106,210, dated August 9, 1870.

BROILER.

The Schedule referred to in these Letters Patent and making part of the same.

To all whom it may concern:

Be it known that I, DAVID E. ROE, of the city of Elmira, in the county of Chemung and State of New York, have invented a new and useful Improvement in Broilers; and I do hereby declare that the following is a full, clear, and exact description of the construction and operation of the same, reference being had to the annexed drawing making a part of this specification, in which—

Figure 1 is a vertical section, and

Figure 2, a top view of the gridiron.

The letters of reference refer to the same parts in each figure.

The nature of my invention consists in making a broiler in such shape that it may be used upon stoves that have various-sized holes, and, at the same time, have it light, strong, and durable; also, having it provided with a gridiron of peculiar construction, that makes it neat and clean, and easy to manufacture, and durable.

To enable others skilled in the art to make and use my invention, I will proceed to describe its mode of construction and operation.

A is the body or main portion of the broiler that supports the various parts. It may be made of sheet or cast metal, as preferred, and of any desired size. It may be made in shape as the frustum of a cone inverted, or segment of a sphere, from any portion of the sphere to give the required shape. At any place between the upper and lower edges is a groove, to lay the gridiron within, as shown in fig. 1. The lower diameter must be so that it will fit within the smallest holes in the stove to which it may be applied, while the upper diameter must be so great that the broiler

may be placed on a much larger hole; and, when thus made, the broiler may be used on different-sized holes that are made in the various kinds of stoves in general use.

The broiler is provided with a cover and handle of any ordinary construction, and the body or groove may be varied, to suit the various kinds of gridiron that may be applied within it.

B is the gridiron. It is made of wire, and is shaped as shown in fig. 2.

The outer rim C is made as a hoop, with the upper and lower portions of the wire dented, to hold the wires D in proper position.

The radial wires D are bent around a ring, to hold them all together at the center. The outer ends are bent around the wire C or rim, and are held in place by being laid in the dents, or held by small whipping-wire.

The diameter of the gridiron must be the same as the diameter of the groove in the body A.

Having thus fully described my invention,

What I claim as my invention, and desire to secure by Letters Patent, is—

The improved broiler herein described, composed of the conical or equivalent-formed body A, provided with the groove, or its equivalent, in the inner side thereof, in combination with the removable gridiron B, resting in the said groove, substantially as and for the purpose herein specified.

DAVID E. ROE.
